UNITED STATES PATENT OFFICE.

WILLIAM KNUDSEN, OF FREMONT, NEBRASKA.

MANIFOLD FOR INTERNAL-COMBUSTION ENGINES.

1,124,916.

Specification of Letters Patent. Patented Jan. 12, 1915.

Application filed June 18, 1914. Serial No. 845,932.

To all whom it may concern:

Be it known that I, WILLIAM KNUDSEN, a citizen of the United States, residing at Fremont, in the county of Dodge and State 5 of Nebraska, have invented certain new and useful Improvements in Manifolds for Internal-Combustion Engines, of which the following is a specification.

The present invention relates to internal 10 combustion engines and more particularly to the means for introducing the carbureted mixture into the working cylinder.

It is frequently desirable to employ kerosene or the like for fuel in an internal combustion engine that is otherwise constructed for use with gasoline and even when employing this lighter distillate it may be desirable to condition the mixture by heating, just before admitting it to the working 20 cylinders.

The primary object of the invention is to provide a manifold for internal combustion engines whereby the mixture for combustion in the cylinders is heated by means 25 of the waste heat from the exhaust pipe.

A further object of the invention is to provide means which may be conveniently used in connection with a manifold, as above mentioned, whereby steam may be generated 30 and supplied to the mixture in its travel through the manifold.

To these ends the invention is embodied in the various combinations of parts herein-after described at length and particularly 35 set forth in the claims.

In the drawing which accompanies this specification, Figure 1 is a side elevation of an engine having a carburetor and manifold embodying the features of the invention; 40 Fig. 2 is a vertical section of the manifold showing the relation of the parts; Fig. 3 is a transverse section on the line 3—3, Fig. 2; Fig. 4 is a vertical section on the line 4—4, Fig. 2; Fig. 5 is a transverse section on the 45 line 5—5, Fig. 2.

Referring to the drawings in detail, A, B, and C represent the power cylinders of an internal combustion engine constructed in any well known manner. D represents the 50 carburetor which is also constructed in any well known manner.

1 represents an exhaust manifold having exhaust receiving ports 2, 3 and 4 adapted for immediate attachment to the exhaust 55 ports of the engine.

5 represents a suitable exhaust passage.

6 represents the fuel supply manifold which is inclosed in the exhaust manifold 1 and constructed with a fuel constituent inlet 7, and suitable fuel supply ports 8, 9 and 10 adapted for immediate attachment to the fuel intake ports of the engine. The fuel constituent passage is also constructed with two branches 7^a and 7^b each communicating with a portion of a fuel supply manifold 11 intermediate of its three ports.

It will be observed that both the exhaust outlet and the fuel intake are intermediately located in the combined exhaust and fuel manifolds and that the ports with which they connect are distributed on opposite sides thereof; also that the fuel intake communicates with the fuel delivery ports, through diverging channels while the internal chamber of the exhaust manifold with 75 which its receiving ports communicate, delivers the product of combustion from its opposite ends, through converging channels communicating with the exhaust outlet. It will also be observed that the diverging 80 channels of the fuel manifold extend across the converging channels of the exhaust manifold so that the heating effect is materially increased. In the preferred disposition of the parts, the fuel intake is diametrically 85 opposite the exhaust outlet and the exhaust and fuel delivery ports taken collectively, are symmetrically distributed on opposite sides of the intermediate line. This affords a symmetrical and easily patterned casting, 90 even though an odd number of cylinders, and consequently an odd number of each kind of ports be involved in the application of the invention to an engine.

12 represents a water supply pipe which 95 is adapted to supply water to a suitable steam generating chamber 13 located in the exhaust discharge passage 5.

14 represents a steam supply pipe which is suitably connected to the steam generating 100 chamber 13 and an injector 15 located in the fuel constituent inlet 7.

16 represents a suitable air controlling inlet in injector relation to the steam supply pipe 14.

17 represents a suitable overflow cock for the generating chamber 13.

I claim:

1. An attachment for internal combustion engines, comprising an exhaust manifold 110 and a fuel manifold combined with and enveloped by the exhaust manifold; said ex-

haust manifold being constructed with an intermediately disposed exhaust discharge port and exhaust intake ports distributed on opposite sides of the exhaust discharge port; and said fuel manifold being constructed with an intermediately disposed fuel intake and fuel delivery ports distributed on opposite sides of and in communication with said fuel intake; the exhaust manifold also having converging passageways through which it delivers to its discharge port, and said fuel manifold having diverging passages extending from its fuel intake across the converging passages of the exhaust manifold and leading to the fuel delivery ports.

2. An attachment for internal combustion engines, comprising an exhaust manifold and a fuel manifold combined with and enveloped by the exhaust manifold; said exhaust manifold being constructed with an intermediately disposed exhaust discharge port and exhaust intake ports distributed on opposite sides of the exhaust discharge port; and said fuel manifold being constructed with an intermediately disposed fuel intake and fuel delivery ports distributed on opposite sides of and in communication with said fuel intake; the fuel intake and exhaust discharge port being diametrically opposite each other and the fuel delivery and exhaust receiving ports, collectively, being symmetrically distributed on opposite sides of said intake and discharge port.

3. An attachment for internal combustion engines, comprising an exhaust manifold and a fuel manifold combined with and enveloped by the exhaust manifold; said exhaust manifold being constructed with an intermediately disposed exhaust discharge port and exhaust intake ports distributed on opposite sides of the exhaust discharge port;

and said fuel manifold being constructed with an intermediately disposed fuel intake and fuel delivery ports distributed on opposite sides of and in communication with said fuel intake; the exhaust manifold also having converging passageways through which it delivers to its discharge port, and said fuel manifold having diverging passages extending from its fuel intake across the converging passages of the exhaust manifold and leading to the fuel delivery ports; the internal capacity of the exhaust manifold being sufficiently greater than the external dimensions of the fuel passages to leave in the former, a free circulating space around the latter, and each fuel passage having, for a portion of its length beyond the converging exhaust channels, one wall coincident with the top wall of the exhaust manifold.

4. The combination with the exhaust manifold of an internal combustion engine having exhaust receiving ports adapted for immediate attachment to the exhaust port of the engine, and a suitable exhaust passage; of a fuel supply manifold having a suitable fuel constituent inlet and having fuel supply ports adapted for immediate attachment to the fuel intake ports of the engine; said fuel supply manifold being enveloped by said exhaust manifold, and a steam generating chamber located in said exhaust discharge passage and having a steam delivery connection with the fuel supply manifold, and a controllable air inlet in injector relation to said steam supply pipe.

The foregoing specification signed at Fremont Nebr. this 28th day of May, 1914.

WILLIAM KNUDSEN.
